CLAIM

We claim the ornamental design for a pattern for a paper product, as shown and described above.

DESCRIPTION

The sole FIGURE is a top plan view of a pattern for a paper product, showing our new design;

The pattern indicated by the attached drawing can be applied to a single or multi-ply product. The dashed lines in the FIGURE, which form no part of the claimed design, depict the paper product to which the surface pattern is applied, as well as one repeat unit of the pattern, which repeats indefinitely in one or more directions.
